UNITED STATES PATENT OFFICE.

CHARLES E. CHANCE, OF ANNAPOLIS, MARYLAND.

BOAT FORM.

Application filed June 4, 1926. Serial No. 113,816.

This invention relates to improvements in boat hull building, having for an object to provide a former device especially advantageous for use in the building of boat frames or skeletons whereby the rate of production of such frames may be materially increased and, thus, an appreciable saving of time and labor expenditures effected upon part of a builder, as well as the employment of unskilled labor for such work permitted.

It is likewise an equally important object of the invention to provide a frame of the character mentioned in which the timbers making up a boat frame may be set and bent into the required shape or torsional curvature, following which, they may be then relatively braced, whereupon the complete frame may be easily and quickly removed from the form by reason of the novel and peculiar construction of one side thereof and the form then properly re-assembled and adjusted for the building of another frame.

Other objects of the invention will be in part obvious and in part pointed out herein-after.

In order that the invention and its mode of operation may be readily understood by those skilled in the art, I have in the accompanying illustrative drawings and in the following detailed description based thereupon, set out one possible embodiment of the invention.

In these drawings:

Figure 1 is a side elevation of the improved boat frame form,

Figure 2 is an end elevation thereof,

Figure 3 is a vertical transverse section taken on the line 3—3 of Figure 1 looking in the direction in which the arrows point,

Figure 4 is a similar section taken on the line 4—4 of Figure 1 looking in the direction in which the arrows point,

Figure 5 is a fragmentary enlarged detail in horizontal section taken on the line 5—5 of Figure 1 looking in the direction in which the arrows point,

Figure 6 is an enlarged fragmentary detail in vertical transverse section taken on the line 6—6 of Figure 1 looking in the direction in which the arrows point,

Figure 7 is a similar view in vertical longitudinal section taken on the line 7—7 of Figure 2 looking in the direction in which the arrows point,

Figure 8 is a detail in elevation of the marking gauge employed for the proper

marking of the upper extremities of the shaped or torsionally curved ribs, and

Figure 9 is an enlarged fragmentary detail in vertical longitudinal section taken on line 9—9 of Figure 2 looking in the direction in which the arrows point.

Having more particular reference to the drawings in connection with which like characters of reference will designate corresponding parts throughout, the improved form may be stated to comprise bed timbers or their equivalents, generally designated by the numeral 1, said timbers being arranged in equi-spaced relation whereby to present a longitudinally disposed series thereof, each of said timbers being preferably arranged in relative parallelism, and being substantially square in cross section as is clearly illustrated in the Figure 7. Received upon the upper portions of the bed timbers 1 are pairs of opposed base pieces or timbers 2 and 3, which, as will be noted upon reference to the Figures 7 and 9 are of less widths than are the bed timbers 1; certain of these base timbers being secured in position with respect to the upper or receiving surfaces of the timbers 1 through the medium of securing plates 4 having bolts 5 passed through their opposite end portions into and through adjacent portions of the timbers 1, 2 and 3, whereupon locking nuts or similar devices are engaged therewith for an obvious purpose. In this connection, it is to be noted that the inner or adjacent ends of the base pieces 2 and 3 received upon the timbers 1 are normally arranged in spaced relation and thus provide a pocket or space 6 adapted to receive the keel 7 of a boat frame being built upon the form.

While the majority of the base pieces 2 and 3 are secured to their respective timbers 1 through the medium of the plates 4, certain others thereof are received upon the intermediate portions of the upper surfaces of said timbers 1 and are secured in fixed positions with respect thereto through the medium of cross sectionally L-shaped brackets 8 having fastening bolts passed through the opposite portions thereof into engagement with adjacent portions of such pieces 2 and 3 and the timbers 1. In this connection, it will be understood that the necessity of these cross sectionally L-shaped securing plates is occasioned by the fact that their respective base pieces 2 and 3 are not arranged adjacent or flush with certain of the sides of

the base timbers 1 as is the case with the majority of such base pieces, the utility of which will be subsequently described.

Because of the fact that the boat frame to be constructed upon my improved form decreases in depth toward the stern portion thereof, it becomes necessary that cradle blocks 9 shall be secured to the inner portions of the upper surfaces of certain of said base pieces 2 and 3, as shown in the Figure 3, whereas sub-base pieces 10 and 11 are supported upon the upper portions of those base pieces 2 and 3 adjacent or in proximity to the stern forming portion of the form, as is shown in the Figure 2.

Frame side forms or standards are rigidly carried upon the outer portions of certain of the base pieces 2 and 3 and the sub base pieces 10 and 11, such standards being generally designated at this time for the purpose of convenience by the numeral 12 and each thereof having their inner surfaces or marginal portions curved as at 13 to conform to the required torsional curvature of the boat ribs constituting the frame; the lower or basal portions of the standards 12 being curved inwardly with respect to each other as indicated at 14; such surfaces flushly joining with the substantially flat upper surfaces of the inner portions of their respective or adjacent base pieces 2 and 3, cradles 9 and sub base pieces 10 and 11, whereby to permit of the proper formation of the bottom of the boat frame. It is preferable in this connection, that the frame side forms or standards 12 shall be relatively braced with respect to the particular pieces carrying the same through the medium of diagonally disposed bracing bars 15 secured to adjacent portions of such standards, base pieces or sub base pieces through the medium of appropriate fastening devices; it being noted in this connection that those portions of the bracing bars 15 adjacent the curved portions 14 of said standards 12 are cut away and curved to conform therewith and thus permit of the proper casing of the frame ribs. Likewise, it will be noted upon reference to the Figure 4, that the frame side standards 12 adjacent the bow portion of the form represent, upon their inner or adjacent surfaces, a torsional curvature of different degree and that the lower portions of these particular standards are "set in" with respect to the adjacent portions of their particular base pieces 2 and 3 and are secured to such base pieces through the medium of fastening devices generally indicated at 16, while diagonally disposed bracing bars 17 are employed to effect rigid positioning of certain forward or bow shaping standards with respect to their particular base pieces 2 and 3, as is shown in the Figure 4. The lower and inner extremities of these particular standards 12,

however, are relatively spaced whereby to provide for the keel receiving pocket or space 6, aforesaid.

The intermediate and rearward or stern frame side standards 12 have vertically disposed pieces 18 secured to the inner and normally spaced ends of their particular base pieces 2 and 3 while the upper portions of said pieces 18 are secured to adjacent portions of either the cradle blocks 9 or the sub base pieces 10 and 11, whereby to further insure the forming of a continuous keel receiving pocket or space 6.

To effect a further bracing of the intermediate and aft or stern frame side standards 12 with respect to their particular base pieces 2 and 3, diagonally disposed trusses or bracing bars 19 may be and preferably are employed, the extremities of such bars being secured to adjacent portions of the standards 12 and to the outer side portions of the adjacent pieces 2 and 3 in the manner shown in the Figures 2 and 3; it being noted in this connection, that those particular standards 12 carried upon the sub base pieces 10 and 11 have their respective bracing bars 19 secured as at 20 to the adjacent outer side portions of said sub pieces 10 and 11, thus effecting the relative interconnection and bracing of each thereof.

A bow member 21 is arranged upon the upper surface and intermediate portion of the foremost bed timber 1, as is shown in the Figure 1 and in this connection, it is to be understood that the basal or lower portion of this bow member is directly adjacent and secured to the forward end of the keel arranged in the pocket 6, whereby to effect proper alignment of the boat frame bow with the keel thereof.

To effect interconnection of the relatively spaced series of boat frame forms as constituted by the opposed pair of base pieces 2 and 3, the sub base pieces 10 and 11 and the various frame side standards 12, I employ a plurality of longitudinally disposed stringers generally designated herein by the numeral 22, said stringers extending for approximately the entire length of the boat frame form so constituted and inset with respect to the curved inner surfaces of the standards, the cradle blocks 9 and the inner portions of the upper surfaces of the sub base pieces 10 and 11 as to effect the shaping of the adjacent portion of the frame bottom; the adjacent portions of said stringers 22 being suitably secured to their respective standards 12 cradle blocks 9 or base pieces 10 and 11 whereby to prevent displacement of relative movement therebetween. Furthermore, angularly disposed bracing bars 23 are interpositioned as between the relatively longitudinally spaced form units constituted by the standards 12 and their base or sub base pieces 2, 3, 10 and 11 and in this way,

it will be understood that such form units will be positively retained in their respective position and against relative movement so as to at all times be in relative parallel relationship. Likewise, it will be understood that the upper portions of these angularly positioned sides 23 will serve to brace the adjacent portions of certain of the longitudinally disposed stringers 22.

10 From the construction so far explained, it will be understood that I have provided a boat frame form consisting of a plurality of form units, such units being each constituted by bow, intermediate and stern positioned standards or frame sides 12, cradle blocks 9, such base pieces 10 and 11 and base pieces or timbers 2 and 3 the said form units being relatively interconnected through the medium of the spaced and longitudinally disposed stringers 22, such stringers being so arranged as to permit of the shaping of a boat frame or skeleton of the generally required contour, wherein the bow portion thereof is of greater depth, the frame decreasing in its depth toward and to the stern portion of the same whereat it is gradually broadened in beam as is clearly illustrated in the Figure 2.

In using the improved boat frame form, frame units constituted in the manner hereinbefore described, are properly adjusted with respect to each other and then secured through the plates 4 and 8 to the adjacent portions of their respective bed timbers 1, the boat keel K is laid within the form, particularly, within the keel receiving pocket or space 6, hereinbefore described. This keel K, as will be understood, is of conventional formation and extends for approximately the entire length of the boat frame form, the keel being properly positioned and centered with respect to the form through the usage of adjusting wedges generally designated by the numeral 26. These wedges, as will be noted, are driven between the opposite side portions of the keel K and the adjacent end portions of the base pieces 2 and 3 and the sub base pieces 10 and 11 in a manner whereby to assure faithful and proper centering or alignment of such keel with the boat frame form. Any numbers of these wedges 26 may of course be employed for this centering adjustment of the keel K, such as conditions or preference may dictate. Following this, the usual boat frame or hull ribs, after having been effectually steamed, are arranged transversely of the stringers 22 constituting the frame form proper. These steamed ribs are flexed so as to lie adjacent to the particular portions of the stringers 22 receiving them, whereupon work clamps such as indicated by the numeral 24 are engaged therewith and with adjacent portions of the stringers 22 as is shown in the Figure 3. In this way, it will be un-

derstood that the boat ribs R will be positively held adjacent and in contact with the corresponding portions of the stringers 22 so that with drying thereof, they will assume a shape corresponding to the inner surfaces of that general contour afforded by the arrangement of the stringers 22 upon the frame sides or standards 12, the cradle blocks 9 and the sub base pieces 10. With setting and shaping of the transversely curved frame ribs R, the usual gunwale strips 25 may be arranged within the upper and opposite side portions of the ribs R in the manner shown in the Figure 3, being secured thereto in a suitable fashion, while if desired and practicable, carlings or deck beams (not shown herein) may be also engaged with such shaped ribs R whereby to effect a positive interconnection of the parts of the shaped boat frame within the form.

When the boat frame has set for the required period of time, the work clamps 24 may be disengaged from the ribs R and the stringers 22 whereupon a gauge bar 27 is arranged upon the upper surfaces of the gunwale strips 25, it being noted in this connection, that the said gauge bar 27 is formed of angle metal and has the opposite extremities of the vertical portion thereof cut away as is indicated at 28 whereby to flushly engage with the upper surfaces of said gunwale strips 25, the opposite extremities of said gauge bar representing straight edges whereby markings may be made upon the adjacent surfaces and upper extremities of the shaped ribs R, following which such ribs may be trimmed to remove the upper and superfluous extremities thereof, preferably, flush or substantially flush with the adjacent portions of the upper surfaces of the gunwale strips 25. With trimming of the ribs R, the boat frame is now ready for removal from the form and to effect such removal, the bolts 5 securing the lower portions of certain of the securing plates 4 and 8 to the bed timbers 1 are removed, whereupon one complete side of the boat frame form is slid from the base timbers 1, thus exposing the adjacent side of the boat frame and permitting such boat frame to be readily slid or similarly removed from the form. With removal of a boat frame from the form, it may be understood that the previously removed side of said form is then replaced and re-secured with respect to the bed timbers 1 whereupon the form is then ready for another frame building operation.

From the foregoing, it will be understood that I have provided a boat frame form which by reason of its novel construction and arrangement of parts, will serve to materially facilitate the construction and likewise, increase the rate of speed at which boat frames or skeletons can be completed, permitting also, because of the manner of build-

ing or assembly of the elementary parts of a boat frame, of the employment of unskilled labor and hence, effecting a material reduction in incident expenditures upon part of a boat builder.

Manifestly, the construction shown is capable of considerable modification and such modification as is within the scope of my claims, I consider within the spirit of my invention.

I claim:

A form of the character described comprising a plurality of juxtaposed longitudinally arranged and relatively spaced bed timbers, pairs of opposed base pieces received upon said timbers, cradle blocks carried upon the inner portions of the upper surfaces of certain of said base pieces, sub base pieces rigidly supported upon the upper portions of certain others of said base pieces, frame side forms carried by each of said base pieces, the inner surfaces of said forms being curved inwardly to conform to the required traverse curvature of the boat ribs to

be received thereby and said curved inner surfaces joining with the curved inner surfaces of adjacent portions of said cradle blocks and sub base pieces, the inner ends of said base pieces and said sub base pieces being relatively spaced whereby to provide a keel receiving pocket therebetween, bracing means connected to the inner extremities of said sub base pieces and the corresponding portions of their respective base pieces adjacent said keel receiving space, a plurality of longitudinally disposed transversely spaced stringers received upon the inner surfaces of said side forms, cradle blocks and sub base pieces and fixed with respect thereto, means for relatively bracing and interconnecting the various frame side forms arranged upon the juxtaposed bed timbers, and means for securing base pieces against relative movement upon their respective bed timbers at certain times.

In witness whereof I have hereunto set my hand.

CHARLES E. CHANCE.
